UNITED STATES PATENT OFFICE.

WILLIAM ERNEST TURNER, OF DENTON, ENGLAND, ASSIGNOR TO TURNER, ATHERTON AND COMPANY, LIMITED, OF DENTON, NEAR MANCHESTER, ENGLAND.

DESIGN FOR A RUBBER BAG OF HAT-BRIM-PRESS MACHINES.

45,975.

Specification for Design.

Patented June 16, 1914.

Application filed January 28, 1913. Serial No. 744,772. Term of patent 14 years.

To all whom it may concern:

Be it known that I, WILLIAM ERNEST TURNER, a subject of the King of Great Britain and Ireland, residing at Denton, England, have invented a new, original, and ornamental Design for the Rubber Bags of Hat-Brim-Press Machines, of which the following is a specification, reference being had to the accompanying drawing, forming part thereof.

Figure 1 is a perspective view of the bag.
Fig. 2 a geometric plan of the bag.

I claim,

The ornamental design for a rubber bag for hat brim press machines, as shown.

WILLIAM ERNEST TURNER.

Witnesses:

F. C. PENNINGTON,
F. D. BAILEY.
